COUPLER CARRIER

John E. Flesch, Chicago, Ill., assignor to American Steel Foundries, Chicago, Ill., a corporation of New Jersey

Application July 21, 1941, Serial No. 403,320

2 Claims.

(Cl. 213—61)

My invention relates to supporting means for railway car couplers and more particularly to a coupler support utilizing resilient means between the shank of the associated coupler and the coupler carrier.

The main object of my invention is to resiliently support a coupler shank on a coupler carrier in a manner such that severe pounding of the shank against the carrier resulting from jolts and irregularities in the track is substantially eliminated. This severe pounding causes unpleasant and objectionable noise and, therefore, another object of my invention is to deaden and reduce such noise to a minimum. A further object of my invention is to reduce wear on the coupler shank caused by rubbing of the shank against the coupler carrier and the above-mentioned pounding.

A specific object of my invention is to resiliently support a coupler by means of a block of resilient material interposed between the coupler carrier and the superposed coupler shank, said resilient block being under compression in normal position of the coupler so that irregularities in the track will not cause lifting of the shank off the wear plate which may be inserted between the resilient block and the shank.

In the drawing, Figure 1 is a top view of a coupler carrier embodying my invention.

Figure 2 is a front elevation of the structure shown in Figure 1, and Figure 3 is a side view of the carrier shown in Figures 1 and 2.

The coupler carrier generally indicated at 2 comprises spaced side walls 4, 4 having at opposite ends a hook-like structure 6, 6 presenting curved recesses 8, 8 affording a bearing for the trunnion ends of associated hangers or links (not shown) which swingably support the coupler carrier from an associated car part. Each upstanding end portion 10 includes spaced vertical walls 12, 12 integrally formed with the adjacent ends of the side walls 4, 4, said vertical walls 12, 12 defining therebetween a slot 14 adapted to accommodate the shank portion of the associated hanger and to permit lateral swing motion of the coupler carrier. The spaced vertical walls 12, 12 may be joined at their inner ends by substantially vertical transverse end walls 16, 16 which also merge with the side walls 4, 4. Extending between the upstanding end portions 10, 10 and integrally formed with the side walls 4, 4 and the walls 16, 16 is a substantially horizontal web 18 which is disposed intermediate top and bottom edges of the side walls 4, 4 to afford a rectangular pocket 20. A central transverse rib 22 extends

between the side walls 4, 4 beneath the web 18 for reinforcement.

The top surface of the horizontal web 18 affords a seat as at 24 for a substantially rectangular block or member 26 of any suitable resilient material received within the pocket 20. The resilient member 26 has spaced openings 28, 28 extending therethrough for reception within one of their ends of the spaced bosses 30, 30 formed on the web 18 for positioning the resilient member 26. The resilient member 26 may be slightly smaller than the pocket 20 in order to afford space for the flow of the rubber when the resilient member is placed under compression. Seated on top of the resilient member as at 32 is a wear plate 34 of general U-section comprising a top web 36 and depending flanges 38, 38 which externally overlap upper portions of the side walls 4, 4 for limiting longitudinal movement of the wear plate with respect to the coupler carrier. At opposite ends of the wear plate 34 are lugs 40, 40 secured in any convenient manner to the wear plate as by welding. The lugs 40, 40 afford increased area for bearing against the end walls 16, 16 and it may be noted that transverse movement of the wear plate with respect to the carrier is limited by abutment of the ends of the wear plate against said end walls 16, 16. The shank 42 of the associated coupler may be seated on the wear plate as at 44 between the upstanding end portions 10, 10.

It will be understood from a consideration of Figure 3 that during extreme downward movement of the coupler shank 42 the resilient member 26 will flow into abutment with the inner surfaces of the side walls 4, 4, so that the member 26 will be compressed by and between the top wall of the wear plate 34, the side walls 4, 4, and the wall 18 in such manner as to afford a direct force path from each of said walls to every other thereof during said extreme downward movement of the coupler shank. By this arrangement pounding of the coupler shank will be substantially eliminated.

It will thus be readily apparent to those skilled in the art that I have designed a novel coupler carrier mechanism for supporting a coupler shank on a coupler carrier in a manner such that shocks from jars and jolting are cushioned by the resilient member 26, and severe pounding and noise is substantially eliminated.

It is to be understood that I do not wish to be limited by the exact embodiment of the device shown which is merely by way of illustration and not limitation as various and other forms of the

device will, of course, be apparent to those skilled in the art without departing from the spirit of the invention or the scope of the claims.

I claim:

1. A coupler carrier mechanism comprising a carrier with upstanding end portions receiving therebetween a coupler shank, a pocket in said carrier extending between said end portions and comprising a bottom wall and spaced side walls, a block of resilient material seated in said pocket on said bottom wall, a member comprising a top wall between said block and said shank and having depending flanges externally overlapping said side walls, said block being adapted to engage said side walls during extreme downward movement of

15

said shank whereby a direct force path is afforded between each of said walls and every other thereof.

2. A coupler carrier mechanism comprising a carrier, a pocket therein defined by a bottom wall and spaced side walls, a block of resilient material supported on said bottom wall, a member comprising a top wall between said block and said shank, said member having depending flanges externally overlapping said side walls, and said block being adapted to abut said side walls during extreme downward movement of said shank whereby pounding of said shank is substantially eliminated.

JOHN E. FLESCH.
